HEAT EXCHANGE INHALATION MASK

Armand De Angelis, Southbridge, Mass., assignor to
Omnitech Inc., Dudley, Mass., a corporation of
Massachusetts

Filed May 26, 1965, Ser. No. 85,465

Term of patent 14 years

(Cl. D83—1)

FIG. 1 is a front perspective view of a heat exchange inhalation mask showing my new design;

FIG. 2 is a side elevational view;

FIG. 3 is a front view;

FIG. 4 is a sectional view taken on the line 4—4 of FIG. 3; and

FIG. 5 is a sectional view taken on the line 5—5 of FIG. 3.

The broken lines are shown for illustrative purposes only.

I claim:

The ornamental design for a heat exchange inhalation mask, substantially as shown and described.
